UNITED STATES PATENT OFFICE.

FRANK THONE, OF OSKALOOSA, ASSIGNOR TO THE HAWKEYE ELECTRIC MANUFACTURING COMPANY, OF DAVENPORT, IOWA.

RHEOSTAT.

SPECIFICATION forming part of Letters Patent No. 435,985, dated September 9, 1890.

Application filed August 1, 1888. Serial No. 281,636. (No model.)

To all whom it may concern:

Be it known that I, FRANK THONE, of Oskaloosa, in the county of Mahaska and State of Iowa, have invented certain new and useful 5 Improvements in Rheostats, of which the following is a specification.

My invention relates to a variable resistance or rheostat for electric circuits generally, and is designed to afford ready means for varying or regulating the current passing over a given line with care, certainty, and safety, and without the slightest break or interruption of the current in passing from highest to lowest strength, or vice versa. The 10 construction is such that the device may be used with perfect safety with very powerful currents and applied with perfectly satisfactory results to very light or weak currents, thus obviating difficulties common to most 15 forms of rheostat heretofore employed.

In the drawings, Figure 1 is a perspective view of my improved device complete; Fig. 2, a vertical sectional view through the same on line 3 3 of Fig. 3; Fig. 3, a similar sectional view on line 2 2 of Fig. 2.

In the construction of a device of this character it is very desirable to avoid a step-by-step change from one degree of resistance to another, as such change subjects the conductors and instruments to an undue shock, which is liable to work to their detriment, and it is also desirable to have it so simple and durable in construction and of such wide range of capacity that it may be used by unskilled persons with frequency and without great care without danger of breakage or injury. These ends I attain by the construction set forth below, and illustrated in the drawings, in which—

40 A indicates a shell or casing, which, for convenience and economy, I preferably make of cylindrical form, and which I provide with a base-plate B and a cap or cover C, the former being soldered or brazed to the shell, screwed thereon, or otherwise secured in place, and the cap or cover being screwed in place or otherwise so secured as to permit of ready removal when necessary. The base-plate B is furnished with holes a to receive screws, bolts, or other 45 fastenings by which to secure it in position. The shell is furnished on its interior with

sheet-asbestos lining b or other suitable insulating material, sheet-asbestos being preferred because of its indestructibility under high temperatures and its good insulating 55 qualities. The lining b extends over the ends as well as the side walls of the casing, as shown in Figs. 2 and 3, and within the lower end of the shell and resting upon the lining is placed a metal disk D, through the center 60 of which is passed a bolt E, the stem of which extends through and some distance below the bottom plate B. The hole in the base-plate, through which the bolt passes, is enlarged to prevent contact with the bolt, which 65 latter carries immediately below the base-plate a disk, or washer e, of sheet-asbestos, mica, or other good insulator, passes through one end of a metal strap d, and is furnished with a nut e, which latter binds the several 70 parts firmly together. Below nut e one end of a conducting-wire F is coiled about the stem of the bolt, and this wire is firmly clamped between said nut and a washer f by a second nut g, thus making a good electrical 75 contact and permanent connection.

Upon the cap or cover C is placed a sheet or disk G, of asbestos or other suitable insulating material, and above this a top plate H, having an internally-threaded hole at its center to receive a screw-stem I, which stem is furnished at its upper end with a crank-handle or winch J, of non-conducting material, or effectually insulated from the stem, and with a metal hub or collar I'. The lower end 80 of the screw-stem I is advisably, though not necessarily, furnished with an auger-like disk K, which as the stem is screwed up or down serves to loosen up the pulverulent filling L, with which the shell A is supplied, so that the 85 stem may always move freely and without materially compacting the filling beyond its normal condition. The avoidance of a change in the density of the filling is important, for the reason that the conductivity changes with 90 change of density, as is well understood. The top plate H is secured in place by tap bolts or screws l, carefully insulated from and passing through the top plate H and the cap or cover C of the shell, the intermediate insulating-layer G, and the insulating lining b, and screwing into a disk or plate M, which is by 95 100

the lining *b* insulated from cap or cover *C*, and has a central opening sufficiently large to preclude contact with screw-stem *I*.

Above the top plate *H*, and insulated therefrom by strips *h* of sheet-asbestos, mica, or other suitable material, is a raised yoke or cross-piece *N*, secured by insulated screws *i* to the top plate *H* and connected by the metal strap *d* with the bolt *E*, thus affording a path for the current outside of the shell or casing *A* when proper connection is made with yoke or cross-piece *N*.

A wire or conductor *Q* is electrically connected with top plate *H* by a binding-screw *P* or otherwise.

The shell *A* is filled with material in a powdered or finely-granulated state capable of resisting a high degree of heat and of conducting an electric current, but offering a very considerable resistance thereto. It is very important that the filling material be proof against high temperatures because of the heat occasioned by high resistance, and that it offers a very considerable resistance to the passage of an electric current, in order that the device may be utilized for the regulation of powerful currents. Any substantially infusible or non-combustible powder or fine granular substance—that is to say, any substance which will not fuse or burn under practical working conditions and which is a poor conductor of electricity—may be employed; but after many experiments I have adopted and prefer to use a composition consisting of ninety-seven or ninety-eight per cent. of graphite or plumbago and the balance—three or two per cent., as the case may be—of coke in the form of a powder. It is important that both the graphite and the coke be pure, and to this end I find it desirable to wash or soak the coke in sulphuric acid, and subsequently to remove all trace of the acid by washing in pure water. As stated, however, other fillings may be used, very good results being given by the use of graphite alone.

It is apparent that the details of construction admit of considerable variation without affecting the substance of my invention—as for instance, by making the lining of the sides and bottom in one piece, of gutta-percha or equivalent material, employing a sliding stem, with or without an actuating-lever to move it longitudinally, substituting a wire for the metallic strap *d*, and in other ways that will readily suggest themselves to the electrician and the mechanic. The shell or casing is made of a length and diameter proportionate to the use for which the device is designed, and will in every case be large enough to contain a sufficient quantity of material and length of column to afford the maximum resistance likely to be required when the whole or substantially the whole, column is brought into circuit. Assuming the device to be in a circuit, and that it is desired to prevent the passage of any material part of

the current over such circuit, the stem *I* will be raised to its highest point, thus carrying the hub or collar *I'* away from the yoke or cross-piece *N* and the lower end of stem *I* away from bolt *E*, leaving the entire intervening body of graphite or other filling as a resistance to the current, and thus effectually preventing the passage of any material or considerable portion thereof. If, now, it be desired to permit the current to pass, the stem *I* is lowered through the filling material a greater or less distance, as indicated in Fig. 2, causing the lower end of the stem to approach the head of bolt *E* and lessening the length of the intervening body of material, the resistance decreasing and the flow of the current increasing as the distance between the stem *I* and bolt *E* lessens. The length of stem *I* is such that before it shall quite reach the head of *E* the hub or collar *I'* shall make contact with yoke or cross-piece *N*, as shown in Fig. 3, and this being electrically connected with bolt *E* by metallic strap *d* the current will pass by said yoke and strap directly to bolt *E*, and consequently to wire *F*, outside of shell or casing *A* without any appreciable resistance.

The device permits a very gradual or a measurable-quick variation of current over the line, without shock or break, with perfect ease and with safety to operator and instruments or machinery.

I am aware that pulverized carbon has been employed as a resistance, and that provision has been made for varying the resistance by varying the degree of compression of the carbon. I am not, however, aware that it has ever before been proposed to employ as a resistance a practically non-combustible dry powder, and this I desire to claim broadly.

Having thus described my invention, I claim—

1. A variable resistance or rheostat for electric circuits, consisting of a body of practically non-combustible matter in the form of a dry powder and circuit-connections at opposite sides or ends of said body.

2. In a variable resistance or rheostat for electric circuits, the combination of a shell or casing, a body of dry practically non-combustible powder contained therein, and circuit-connections at opposite sides or ends of said body, one movable toward and from the other through the mass of powder and adapted by such movement to lessen the distance between the nearest approaching points of the circuit-connections.

3. The herein-described rheostat or variable resistance, consisting of a shell or casing containing a powdered substance capable of offering resistance to the passage of an electric current, a circuit-connection at one end of the shell insulated therefrom but in electrical connection with the powder therein, a cap or cover, a plate having a threaded hole and insulated from the cap or cover, and a screw-stem threaded to fit said hole and adapted to

- move longitudinally into or through the powder contained in the shell in contradistinction to merely bearing upon and varying the compression of the powder.
5. In combination with shell A, having base-plate B and cap C, filling L, insulating-lining b, bolt E, top plate H, and screw I, passing through said plate and into the filling, substantially as described and shown.
10. 5. In a rheostat or variable electric resistance, the combination of a shell or chamber, a filling of powdered material capable of affording a proper resistance to an electric current, a circuit-connection at each end of the shell or chamber, one movable relatively to the other, a contact hub or block carried by the movable contact, and an electric conductor placed in the path of said hub or block and in electrical connection with the opposite circuit-connection, whereby the current is caused to pass around the resisting body or filling when the two circuit-connections are brought into close proximity.
15. 6. In combination with shell A, having insulated bolt or binding device E and filled with a resisting-powder, insulated plate H, and stem I, passing through said plate and provided with screw-disk K, substantially as shown and described.
20. 7. The combination, substantially as set forth, of shell A, provided with a resisting- filling, base-plate B, lining b, disk D, bolt E, cap or cover C, insulating material G, top plate H, and stem I, passing through said plate and extending into the filling.
35. 8. The combination of shell A, provided with a resisting-filling, base-plate B, lining b, bolt E, cap or cover C, insulation G, top plate H, and screw-stem I, provided with screw-disk K.
40. 9. The herein-described rheostat, consisting of a shell or casing A, containing a powdered resisting material, base-plate B, insulated bolt E, cap or cover C, insulated plate H, stem I, provided with collar or hub I' and passing through plate H, and yoke or cross-piece N, insulated from plate H, located in the path of hub I' and electrically connected with bolt E.
45. 10. In combination with a shell or casing and a resisting-powder contained therein, circuit-connections in electric connection with the filling at separated points, one of said connections being movable relatively to the other, and provided with an agitating device to prevent the compacting of the powder.
50. In witness whereof I hereunto set my hand in the presence of two witnesses.

FRANK THONE.
